UNITED STATES PATENT OFFICE.

HENRY A. MANN, JR., OF BALLSTON SPA, NEW YORK.

ENVELOPE-MACHINE.

SPECIFICATION forming part of Letters Patent No. 291,614, dated January 8, 1884.

Application filed September 30, 1882. (No model.)

To all whom it may concern:

Be it known that I, HENRY A. MANN, Jr., a citizen of the United States, residing in Ballston Spa, in the county of Saratoga, in the State 5 of New York, have invented certain new and useful Improvements in Envelope-Machines, of which the following is a full, clear, and exact specification, reference being had to the accompanying drawings, which form a part 10 hereof.

This invention relates to certain improvements in that class of machines employed in folding envelope-blanks that have previously been cut to the proper shape for the purpose, 15 and wherein the said blanks in quantities are placed upon a suitable feed-table or elevating-support, and thence one by one automatically taken by the mechanism and gummed, folded, and delivered in a completed condition to the 20 apparatus for drying, counting, or bunching the same.

It will of course readily be understood by all persons versed in the art to which this invention appertains that certain constituent 25 elements of my improved machine not herein shown or particularly described may be and are constructed to operate in ordinary manners, or in any way suitable for properly effecting the desired result.

While believing that the machine embodying my improvements is novel and original with me, I will particularly point out the features on which I especially rely, viz: the combination and arrangement of the mechanism 30 for operating the gummer and the pushing-fingers, as hereinafter explained; also, in the pushing-fingers operated by an oscillating lever, which fingers push forward the envelope-blank as it is taken by the plate from the gummer as it rises, so that the blank is caught between the carrying-rollers and passed on; also, 35 in the folder placed between the second pair of creasing-rollers and between them and the pressing-rollers, with its curved or folded sides so arranged as to fold one side of the envelope and partly fold the upper flap; also, in the mechanism which carries forward the envelope-blank through the machine, consisting of the pushing-fingers with projecting pins, 40 platform, the first set of carrying-rollers with folder between them, a second platform with

a guard on its outer edge, a lever, and oscillating attachments, and a second set of carrying, creasing, and pressure rollers. I attain these objects by means of the mechanism illustrated in the accompanying drawings, in 55 which—

Figure 1 is a plan view of the entire machine; Fig. 2, a perspective view of the mechanism combined and arranged to operate the 60 gummer and pushing-fingers; Fig. 3, a view of the creasing and carrying rollers on the first pair of shafts; Fig. 4, a perspective view of the folder, shown in Fig. 1 immediately after the first pair of creasing-rollers; Fig. 5, 65 a perspective view of the folder, looking from the platform; and Fig. 6, a sectional longitudinal view immediately to the left of the central part of the machine, as shown in Fig. 1.

Similar letters refer to similar parts throughout the several drawings.

A is one of the four guide-posts to keep the pile of envelope-blanks straight and in proper position as they are fed up to be gummed.

B is the gummer that lifts the envelope-blank, and b are the guides to keep gummer B in a vertical plane.

C is the plate that removes the envelope-blank from the gummer and deposits it on the carrying-fingers.

D is the weight that brings back the gummer after it is charged with gum.

E represents the gum-box and roller.

F represents the pushing-fingers that carry the envelope to the creasing-rollers.

G is the lifting-lever, weighted at g, that lifts the gummer.

H is the drop-lever for squaring the envelope by friction as it is being pushed between the first set of creasing-rollers.

I is the snail-cam that operates gummer B and lifting-lever G.

K represents the carrying-rollers on the first pair of shafts and between the creasing-rollers K', as shown in Fig. 3.

L represents the fingers that keep the envelope-blank flat while it is being folded.

M, with its curved sides m, is the folder which folds the ends of the envelope-blank in the creases made by rollers K'.

N represents the carrying-rollers between the flat rollers N'.

O is the platform on which the envelope-blank is deposited by carrying-rollers N, o being the guard thereof.

P is the pushing-lever, with a flat end piece 5 set at a right angle to it, for pushing the partly-folded envelope between the second set of rollers.

R represents the creasing-rollers for creasing both sides of the long way of the envelope.

10 S are the carrying-rollers for keeping the envelope straight, or in proper direction, as it passes through the folder.

T is the folder for folding the envelope the long way.

15 U is the roller for pressing down flat the lower previously-pasted flap of the envelope, and U' is a narrow roller for pressing only the edge of the upper flap.

V is a right-angled lever, moving in a slot, 20 for drawing gummer B back over the gumming-roller.

W is a lifting-strap operating lever V.

X is a lifting-strap operating lifting-lever G.

25 Y is an oscillating lever pivoted in its center, and connected at one end with the bent bar y, and at the other end with a rod pivoted on the bar to which the pushing-fingers are affixed.

30 Z is an oscillating lever, pivoted in its center and at one end to pushing-lever P.

The mode of operating my machine is as follows: The envelope-blanks, having been properly cut, are piled in a considerable quantity 35 on an automatic platform or feed-table, (not shown,) that being situated immediately beneath the gummer, the blanks being kept in proper position by means of the four guide-posts, two of which are located at A. The

40 machine then being put in motion by means commonly used for such a purpose, the snail-cam I, acting on the lifting-strap X, raises the gummer B by means of the lever G, which lever is weighted at g to cause it to fall to its original position, and said cam, revolving, acts 45 on the lifting-strap W. That raises the lower arm of the right-angled lever V and causes the gummer to be brought back over the gumbox E. The said cam having now passed from

50 beneath the lifting-strap W, the weight D pulls the gummer back to its position on the plate C, and the lower edges, which project below said plate, being charged with gum, adhere to the envelope-blank on the top of the pile.

55 The cam now begins its second revolution, thereby raising the gummer as before, but with the envelope-blank attached, the same being freed from the gummer B by the plate C, and deposited on the ends of the pushing-fingers F. These fingers have a projecting

60 pin, f, to push the envelope-blank across the plate C and between the carrying-rollers K, as said fingers are moved forward by the lever Y, attached to the wheel a by a slightly-bent bar, y.

65 While the gummer is operated as before, said envelope-blank is urged forward by the rotary motion of the carrying-rollers K,

and kept in proper position by means of the drop-lever H. The blank is now creased by the creasing-rollers K', and passes through the 70 folder M, the curved sides m of which fold the ends of the envelope-blank, which blank is held in position by the fingers L, pressing lightly in the creases made by creasing-rollers K'. The said blank is now caught by the second pair of carrying-rollers, N, and conveyed

75

through the flat rollers N', which press the folds just made and deposit said blank upon the platform O. The lever P, operated by the oscillating lever Z, pushes the blank at a right 80 angle into the second pair of creasing-rollers.

These latter crease the sides of the envelope and carry it to the rollers S, which push it squarely through the folder T, where the lower flap is folded flat and the upper flap partly 85

folded, and thence the envelope passes between the rollers U and U'. While thus passing the wide roller U presses the previously-pasted lower flap of the envelope and the narrow roller U' presses the fold of the upper crease. 90

It is now, by means of an endless belt (not shown) or other familiar device, delivered ready to be dried, counted, or bunched.

It will be observed that the first set of creasing-rollers, K', are placed on shafts, one 95 above another, as shown in Fig. 3. The upper roller has a tongue projecting from its edge, which fits into a corresponding groove in the lower rollers.

On the center of the shaft bearing the upper rollers is a carrying-roller with 100 a beveled edge acting on another and wide-rimmed roller beneath, so nearly touching each other as only to leave room for the envelope-blank to pass and press between. The second set of creasing-rollers, R, has no carrying-rollers 105 between them, as they themselves carry the envelope forward.

For the purpose of adapting my machine to the manufacture of any desired size of envelopes, I make various parts adjustable by means 110 of set-screws and other appliances well known to practical mechanics. Thus the guide-posts A may be shifted in slots to suit the size of the envelope-blanks. The rollers, being loosely

set on their respective shafts, may, by set-screws or jam-nuts, (not shown,) be rigidly fixed at the proper distance apart, and the folder M and the platform O, with its rim o, may be contracted or expanded in width, so as

115 to change the distance apart of the devices hereinbefore described for folding the ends or flaps of the envelope-blanks by slides and other devices analogous to those used in dining-tables, on machine-beds, and other things.

These means must be obvious without further description; but so far as I know, in a machine of the nature of my invention, they are now used and embodied for the first time, and therefore I regard them as novel component parts of my invention, and of great value. 125

130 What I claim as my invention, and desire to secure by Letters Patent, is—

1. In an envelope-machine, the combination, substantially as hereinbefore described, of the

- cam I, lifting-strap X, lifting-lever G, lifting-strap W, right-angled lever V, guides b, and weight D, all operating the gummer B, the gummer B and its parts, the plate C, platform C', gum-box and roller E, pushing-fingers F, operated by the oscillating device composed of the oscillating lever Y and its attachments, drop-lever H, carrying-rollers K, and creasing-rollers K', folder M, and fingers L, carrying-rollers N, and flat rollers N', platform O, with its guard o, lever P, actuated by oscillating lever Z and its attachments, creasing-rollers R, carrying-rollers S, folder T, and rollers U and U', all being constructed and organized for operation as set forth. 15
2. In an envelope-machine, the combination and arrangement, as hereinbefore described, of the gumming apparatus B, gum-box and roller E, operating mechanism I, X, G, W, V, b, and D, and their attachments, all being constructed and organized as hereinbefore specified. 20
3. In an envelope-machine, the pushing-fingers F, with their projecting pins f, operated by the oscillating device, consisting of the oscillating lever Y and its attachments, in combination with gummer B, all constructed, arranged, and operating as hereinbefore specified. 25
4. In an envelope-machine, the combination and arrangement of the creasing-rollers K' and R, folder M, with its curved sides m, guiding- 30
- 35 fingers L, platform O, and the lever P, operated by the oscillating device Z, all constructed, arranged, and operating as set forth and described. 35
5. In an envelope-machine, the combination and arrangement of the carrying mechanism, consisting of the pushing-fingers F, with pins f, platform C', carrying-rollers K, creasing-rollers K', and carrying-rollers N, with folder M between them, platform O, with guard o, lever P, and oscillating attachments, and rollers R, S, U, and U', all being constructed and organized for operation as set forth and described. 40
6. In an envelope-machine, the folder T, having curved or folded sides, as shown, and the rollers U and U', so that the lower flap is folded, pressed flat, and sealed, while the seal-flap is folded and its fold only is pressed without sealing the flap, all being constructed and arranged as hereinbefore specified. 45
7. In an envelope-machine, the combination and arrangement of the creasing-rollers R, the carrying-rollers S, the folder T, and the pressing-rollers U and U', so as to fold and press both flaps, and at the same time seal the lower flap of the envelopes, as set forth, and all constructed, arranged, and operating as hereinbefore shown and described. 50
